United States Patent Office.

LEWIS B. COVERT, OF NEW YORK, N. Y.

Letters Patent No. 77,463, dated May 5, 1868.

IMPROVED EXTENSION STEP-LADDER.

The Schedule referred to in these Letters Patent and making part of the same.

TO ALL WHOM IT MAY CONCERN:

Be it known that I, LEWIS B. COVERT, of the city and State of New York, have invented and made a certain new and useful Improvement in Step-Ladders; and I do hereby declare the following to be a full, clear, and exact description of the said invention, reference being had to the annexed drawing, making part of this specification, wherein—

Figure 1 is a vertical section of said step-ladder partially extended.

Figure 2 is an elevation of the same.

Similar marks of reference denote the same parts.

This invention relates to a step-ladder that can be extended, for increasing its height, or folded into a small compass, for storing away, or for transportation.

My ladder is formed of side-pieces, with two-part steps, between which a frame is fitted to slide, and carries swinging steps, that can be turned down flat, and held by keys, or turned up edgewise, to pass between the two-part steps when the frame is being moved in opening or closing the step-ladder. The back legs are made to extend as the ladder is raised.

By this construction, the ladder can be extended step by step, as required, up to the extreme length, or placed at once at any intermediate point, thus largely increasing the facility with which the ladder can be employed under varying circumstances.

In the drawing, *a a* are the side-pieces of the ladder; *b b*, the two-part steps, the parts being securely united together.

The side-pieces *a* have grooves formed in their inner faces, in which the extension-pieces *c c* slide. These pieces *c* are united firmly, near their middle and lower end, by the cross-bars *d*, and at the upper end by the top step *e*.

The upper ends of the side-pieces *a a* are strengthened by the metal straps *f*, seen also in Figure 3, and a bolt, *i*, passing through each of these metal straps, enters the piece *c*, to hold the same when extended, the said pieces *c c* having cavities in their outer surfaces, at the same distance apart that the steps *b b* are placed, so that the ladder may be extended the height of one or more steps.

Upon the inner faces of the extension side-pieces *c c*, I fasten metal castings, *g g*, formed as seen in larger size in Figure 4. The distance that these are apart corresponds with the height of step, and I place between them swinging steps *h h*, that are set to turn upon pivots *2*, so that they may pass down edgewise between the two-part steps *b*, or be turned down flat for use, as seen in fig. 1.

In order to prevent the steps *h h* swinging in use, when the ladder is extended, I introduce across, beneath each end, a wedge, *3*, that has a dove-tailed edge entering a corresponding groove across the casting *g*, and the other edge, projecting from such casting, supports the end of the swinging step.

A box is provided at *k*, for receiving these wedges *3* when not in use.

l l are the back legs of the step-ladder, hinged, at *4*, to the top step *e*, and united by the cross-bars *m*, and braced by the diagonals *n*.

o o are sliding extension-legs, held to the sides of the respective legs *l* by the metal bands *5*, that allow end-motion, but secure the parts to each other. The pins *6* are employed to prevent end-motion after the parts have been properly extended, said pins being entered into holes provided for them.

In order to brace the legs *o o* when extended, the metal rods *p p* are employed. Each rod is formed with a hook at one end, and a joint to the leg *l* at the other end, and eyes or staples are provided at *7*, into which the hooks are passed at the proper points. When the ladder is not extended, these rods *p* are to be turned upwards, and held by a loop or band, as seen by red lines in fig. 2.

A strap or cord, *q*, attached at its ends to the legs *l*, and provided with a ring near the middle thereof, setting upon one of the hooks *8*, is provided, to prevent the legs *l* moving too far from the step-ladder when unfolded for use.

What I claim, and desire to secure by Letters Patent, is—

1. A step-ladder, formed with the two-part steps *b*, extension-pieces *c*, and their steps, substantially as specified, so that the one ladder can be drawn out from the other, as shown.
2. The swinging steps *h*, supported by the castings *g*, in the manner specified, in combination with extension step-ladder aforesaid.
3. The extension-legs *l* *e*, in combination with the extension step-ladder, provided with the swinging steps, as and for the purposes set forth.

Dated, this third day of March, A. D. 1868.

LEWIS B. COVERT.
